(57) **CLAIM**

The ornamental design for a mounting assembly for a trolling motor as shown and described.

DESCRIPTION

FIG. 1 is an isometric view of a mounting assembly for a trolling motor shown in a state of use, attached to a pontoon boat;

FIG. 2 is another isometric view of the mounting assembly for a trolling motor of FIG. 1;

FIG. 3 is another isometric view of the mounting assembly for a trolling motor of FIG. 2;

FIG. 4 is another isometric view of the mounting assembly for a trolling motor of FIG. 2;

FIG. 5 is another isometric view of the mounting assembly for a trolling motor of FIG. 2;

FIG. 6 is a front view of the mounting assembly for a trolling motor of FIG. 2;

FIG. 7 is a rear view of the mounting assembly for a trolling motor of FIG. 2;

FIG. 8 is a first side view of the mounting assembly for a trolling motor of FIG. 2;

FIG. 9 is a second side view of the mounting assembly for a trolling motor of FIG. 2;

FIG. 10 is a top view of the mounting assembly for a trolling motor of FIG. 2; and,

FIG. 11 is a bottom view of the mounting assembly for a trolling motor of FIG. 2.

The broken lines in the figures depict portions of a mounting assembly for a trolling motor or the environment that form no part of the claimed design. In addition, the surface shading illustrated in the figures is provided merely to highlight the contour of design and is not intended to be illustrative of texture or gloss.
